UNITED STATES PATENT OFFICE.

MOSES G. FARMER, OF ELIOT, MAINE.

TELEPHONIC TRANSMITTER.

SPECIFICATION forming part of Letters Patent No. 378,298, dated February 21, 1888.

Application filed November 2, 1887. Serial No. 254,058. (No model.)

To all whom it may concern:

Be it known that I, MOSES G. FARMER, a citizen of the United States, residing at Eliot, in the county of York and State of Maine, have 5 invented certain new and useful Improvements in Telephonic Transmitters, of which the following is a specification, reference being had to the drawings accompanying and forming a part of the same.

10 The subject of this invention is a telephonic transmitter capable of reproducing articulate speech or other sounds, particularly loud sounds, more distinctly and audibly than the ordinary transmitters heretofore used.

15 The instrument belongs properly to that class of transmitters known as "long-distance telephones;" but its peculiar capabilities of reproducing articulate speech with great clearness and distinctness make it a generally use 20 ful and valuable instrument.

The main object which I have sought in the construction of the device is to maintain a permanent though yielding electrical connection or bridge between the two sides or terminals 25 of the instrument and through one of the electrodes, but independent of the normally-existing path formed by the contact of the two main electrodes. For this purpose, aside from other improvements in the details of construction, 30 to be hereinafter set forth, I support a small plumbago point by a light spring so that it remains in contact with the surface of the vibrating carbon electrode. The range of movement of this carbon electrode is limited, and 35 the spring supporting the plumbago point is so bent that the point is constantly held in contact with the electrode by spring pressure. It results from this that, while the carbon may be thrown out of actual contact with its op-

40 posing metallic point or electrode by sudden or extended vibrations of the diaphragm, the jarring and sputtering sounds produced by ordinary transmitters will not occur, for the great difference in the mass or inertia of the 45 carbon button and the spring-supported point keeps them constantly in contact and prevents an actual break in the circuit.

Figure 1 is a plan view of an instrument made in accordance with my invention. Fig. 50 2 is a side view of the same with a portion of the supporting base or plate cut away. Fig.

3 is a side view of a modified form of the invention with the base in section.

The operative parts of the instrument are conveniently mounted on the base A, through 55 which is a perforation, R. The diaphragm (a sheet or plate, D, of iron, mica, aluminum, or the like) is secured to plate A over this opening. Above this diaphragm two standards, B B, are secured to the base to support a horizontal shaft, L. To said shaft is secured the rigid arm V, carrying at its extremity the cup C, containing the carbon electrode or button h, which in its normal position rests lightly upon the platinum point O, attached to the 60 diaphragm D. An arm, P, is also secured to the shaft L by a sleeve and screw, f. The arm extends in the opposite direction from the shaft to arm V and carries an adjustable counter-balance, W. A screw, d, by adjustment encounters the weight of the arm P and limits the range of play or vibration of the electrode h. A light spring, K, is secured to the shaft L by a screw, f', on the side of the shaft opposite to arm V. An adjusting-screw, e, in contact 75 with said spring, is used to regulate the contact-pressure of the button h on the platinum point O. A standard or bracket, H, is secured to the base A and carries a slender spring, M. To the end of this spring is secured a small 80 non-oxidizable or plumbago point, n, and the spring is so bent that it will follow the electrode h through its range of movement and remain always in contact therewith.

N is one binding-post of the instrument; S, 85 the other. From N a wire, E', leads to bracket H and spring M, while another or branch wire, E, is connected to the diaphragm. The standards or supports B B are connected to the post S by wires F and I.

90 The impulses or undulations are mainly produced in the circuit including the diaphragm, and the electrodes h. O in the arm V; but the yielding nature of the contact between button h and point n contributes also to this effect. With 95 this form of instrument the circuit is not broken by loud or sudden sounds directed against the diaphragm, and a great distinctness and clearness in the sounds reproduced is the result. The great delicacy of adjustment of which the 100 instrument is capable adds very greatly to its efficiency and easy management. I have found

that its operation is not materially affected by the position in which it is used.

The construction of the instrument may be greatly varied, and in one particular more especially, as I have shown in Fig. 3, in which the counterbalancing-arm P is supplanted by the extension V' of arm V, carrying a second carbon-button holder, C', beneath which is an adjustable limiting-stop, O'. In this case the point n is preferably made to bear on the button h'. The binding-post N is connected to the diaphragm, as before, and also, by means of a wire, E'', to the support carrying the spring, to which is secured the point n.

15 The manner of using the instrument is well understood. It may be used either with or without an induction-coil and with any of the ordinary forms of receiver.

What I claim as my invention is—

20 1. In a telephonic transmitter, the combination, with the main electrodes, of an independent conducting-point of relatively small

mass electrically connected to one of the terminals of the transmitter and in permanent yielding contact with the electrodes of the opposite terminals, as set forth. 25

2. In a telephonic transmitter, the combination, with the main electrodes, of a light independently spring-supported carbon point in permanent yielding contact with the vibrating 30 carbon electrode and in electrical connection with the opposite terminal of the instrument, as set forth.

3. The combination, with the shaft L, the arm V and the electrode h carried thereby, 35 the electrode O, the counterbalancing-arm P, and the spring K, of the bracket H, the spring M, and contact-point n carried thereby and bearing upon the electrode h, as described.

MOSES G. FARMER.
